UNITED STATES PATENT OFFICE.

NOEL L. ANTHONY, OF CRANSTON, RHODE ISLAND.

CONVERTIBLE COUCH-BED OR DAVENPORT.

1,182,731.

Specification of Letters Patent.

Patented May 9, 1916.

Application filed May 5, 1915. Serial No. 25,936.

To all whom it may concern:

Be it known that I, NOEL L. ANTHONY, a citizen of the United States, residing at Cranston, in the county of Providence and State of Rhode Island, have invented certain new and useful Improvements in Convertible Couch-Beds or Davenports, of which the following is a specification.

My invention relates to convertible couch-beds or davenports and consists of improvements in the structure and method of operation of the same.

The object of my improvement is to provide a folding couch or bed of simpler structure and more slight appearance than those now in use and particularly to eliminate the complicated and cumbersome mechanism usually employed for operating such devices.

A further object of my improvement is to render the couch more easily and conveniently converted into a bed and, vice versa, from the bed to the couch, and to also provide a greater storing space within the frame or body of the couch when the parts of the latter are in closed relation.

The manner and means for carrying out these improvements are fully described in the following specification, illustrated by the accompanying drawings, in which like reference characters designate like parts.

In the drawings:—Figure 1 is a side elevation of my improved couch showing the parts in closed relation in the form of a davenport; Fig. 2, a cross-sectional view of the couch taken on the line X—X of Fig. 1 and also showing the parts closed together; Fig. 3, a similar view showing the couch open in the form of a bed; Fig. 4, a detail view of a portion of the roller and track construction of the couch frame; Fig. 5, a detail view of one of the supporting side-rollers for the couch-frame; and Fig. 6, a cross-sectional view showing a modification in the structural arrangement of my improved couch.

Referring to the drawings, the main frame or body of the couch is preferably made in the form of a rectangular box B, to provide a storage receptacle for bedding or other articles, but it might also be con-

structed in skeleton form if desired. The box B is usually mounted on relatively short legs b, b which may be provided with casters if desired and which can be made in various ornamental styles when a more elaborate article of furniture is required. The end-sections b', b' of the body B are preferably extended above the top of the side-sections b², b² to conform to the upholstering on the seat-portion of the couch, and if desired may be made in the shape of arms ornamented with carving or scroll-work.

Referring particularly to Figs. 1 and 2, the seat-portion of the couch comprises simply a rectangular frame-member C upholstered on its top and adapted to fit across and close the top of the box or body B. In some cases the member C is made in a box-form to adapt it to receive either a box-spring, so-called, or other arrangements of flexible supports for the upholstery as usually provided in like articles of furniture.

Adapted to be folded into the body B of the couch is a second frame-member C' which forms an extension of the seat-member C when the couch is opened out or converted into a bed as shown in Fig. 3. The extension-frame C' is of the same construction as the member C, equal in length thereof, but of slightly less width to adapt it to fit in between the sides of the body B in a horizontal position. Like the frame C the member C' is upholstered in the usual manner, with or without springs as desired.

For shifting the members C and C' to convert the couch into a bed as illustrated in Fig. 3, I provide a system of guideways or tracks on which run rollers R, R' mounted on the ends of the frames C, C'. Preferably the guideways or tracks are made in the form of plates D let into sides of the end-sections b', b' of the frame B and secured in place by screws s as shown in Fig. 4. Each end-plate D is formed with recessed tracks or guiding-grooves d, d' adapted to receive the rollers R, R' mounted on the ends of the frames C and C'. Preferably a metal strip or plate c is secured to the ends of the wood-portions c'

of the members C, C' and the rollers R, R' are carried on studs r screwed into the plate. The heads r' of the screws r fit into countersunk recesses r² in the rollers R, R' 5 to bring them flush with the outer sides thereof so that the rollers engage the full width of the grooves d, d' without interference of the studs with its side.

Referring to Fig. 3, each plate D has an 10 inclined track or guideway d extending upwardly from a point near one of the sides b² of the body B and nearly across the whole width of the end-section b' of the body. At 15 its top the plate D is formed with a slot or guideway d' extending from a point near the center of the end-section b' substantially half way across the latter and inclined upwardly to a relatively slight degree. At its outer end the lower side of the slot d' is 20 formed with a slight depression or hollow d², see Fig. 3, adapted to act as a detent for the roller R when the latter seats itself therein. The bottom of the depression d² is 25 on a level with the opposite, inner end of the slot or track d' and the roller R is so positioned on the frame C that when it reaches either end of the slot the frame will assume a horizontal position resting on the side b² of the frame B as later described. 30 The track or slot d communicates with the guideway d' through a curved neck-portion or passage d³ at its outer end through which the roller R' may pass when the member C' is manipulated as later described.

35 It will be understood from the foregoing that the two members C and C' are adapted to slide across the top of the couch-frame B and to facilitate their operation in this manner I provide the rollers F, F mounted 40 on the side-sections b², b². These may be of any usual construction and as shown in Fig. 45 are preferably set in bearings in brackets f which are fastened on the inside of the sections b², b² by screws or other means.

50 Any suitable number of rollers F, F may be employed on the frame-sections b², b² as required, four being shown for each side in Fig. 1. Similar, vertical guiding-rolls might also be used on the end-sections b', b', 55 if desired, to guide the ends of the frames C, C', but ordinarily these are not required and are therefore not shown in the drawings. It will be understood that the rollers F, F project slightly above the top of the side-sections b², b² and therefore the members C and C' rest upon and slide across the rollers instead of on the sides of the body B, thus 60 relieving them from unnecessary friction.

In the top of the right-hand side-section b² I provide one or more dowel-holes b³, see Figs. 1, 2 and 3, adapted to receive suitable dowel-pins c² projecting from the under side of the frame C'. The dowels c² are seated in the holes b³ when the frame C'

is pulled out to its extended position 65 and serve to hold the latter in place when the couch is used as a bed. Fastened to the end-sections b', b' of the frame B are suitable blocks or brackets b⁴ on which the ends of the members C' rest 70 when it is lowered into position within the box as illustrated in Figs. 1 and 2. To provide for convenient, manual operation of the frames or members C, C' in drawing them out into open position I attach handles to their outer sides. These may be in the form of straps S, S' as shown in the drawings or if preferred rigid handles can be used.

Having now described the construction 80 and arrangement of the several parts of my improved couch in detail its method of operation will next be explained: When the couch is to be used as a sofa or davenport the seat-member C rests on top of the side-rollers F, F on the frame B with the end-rollers R seated in the hollows d² at the ends of the slots d' to retain the member from lateral displacement. To convert the couch into a bed, the operator grasps the 85 straps S, S and the member C is first pulled out to the left, as shown in Fig. 3, with the rollers R, R traveling in the slots d', d' until they reach the ends thereof to prevent further movement of the member. While 90 the member C is being drawn out in this manner the operator bears down on its outer side to prevent the rollers R, R from dropping down into the slots d, d and a little care in this particular results in a 95 quick traverse of the rollers across the passages d³, d³. The operator now reaches down into the body B and grasps the straps S', S' on the member C' to lift the side of the latter above the top of the side-section b². The 100 member C can now be pulled out of the frame B with the rollers R', R' traveling up the incline of the tracks d, d. As soon as the rollers R', R' reach the end of the tracks d, d the side of the frame C' is 105 pressed downwardly, and with its under side bearing on the side-rollers F, F as a fulcrum the frame is tilted to bring the rollers R', R' up through the passages d³, d³ into the tracks d', d'. The member C' is now 110 pushed back with its rollers traveling in the tracks d', d' to bring its inner side against the side of the member C. As the member C' is thus carried into its rearward position to align it with the member C, care 115 is taken to lift its forward side to seat the dowels c² in the holes b³ and the two members will thus be locked in position to form a relatively broad, flat top to the couch adapted to serve as a comfortable bed. 120

To re-convert the couch into a davenport the member C' is first pulled slowly out to 125 allow its rollers R' to drop through the pas-

slides d^3 , d^4 into the slots d , d , and then pushed back until the rollers reach the lower end of the tracks d , d . The outer side of the frame C' is then lowered down to rest 5 on the brackets b^4 , b^4 as shown in Fig. 2. With the member C' in this position space is provided above it for storing bed linen and other articles and the space below it can also be utilized for the same purpose. If desired a drawer might be fitted in the side of 10 the body B to slide under the member C' and this arrangement would provide for more convenient access to the articles stored in the lower part of the couch.

15 In Fig. 6 I have illustrated another modification of the structure of my improved couch although the method of operation of the top-members remains substantially the same. In this arrangement two separate, 20 independent tracks or guiding grooves g , g and g' , g' are provided for each pair of rollers R , R and R' , R' on the members C and C' . The tracks g , g take the rollers R , R on the seat-member C and are extended 25 more to the left to allow the latter to be pulled out farther. This allows the opposite member C' to be pulled up and out of the body B into its extended position at one operation and the member C is then 30 pushed back against it as shown by the dotted lines in Fig. 6. The rollers R' , R' are mounted on brackets H , H extending downwardly from the under side of the member C' and seat in depressions g^2 , g^2 at 35 the end of the tracks g , g to hold the member from sliding back into the body B . Suitable depressions or sockets g^3 , g^3 are provided in the tracks g , g to locate the member C in its closed position, and if required a dowel-pin can be used to hold the member in place when overhanging the side of the frame B , similar to the arrangement shown in Fig. 3.

40 It will be seen that my improved couch or davenport is of much simpler construction than those now generally in use and is more compact and sightly in appearance. No jointed levers, springs or folding frames are employed to operate its folding parts 45 and therefore its construction is much more economical and durable and less liable to get out of order. Furthermore, when folded together in the form of a davenport all the operating parts are concealed from view, 50 while at the same time a maximum space is provided for storing articles in its body.

55 Various modifications other than those here illustrated might be made in the form and structure of the parts of my improved device without departing from the spirit or scope of the invention; therefore, without limiting myself to the exact embodiment shown and described, what I claim is:—

1. In a convertible couch-bed or daven-

port, the combination with a main frame 65 having end- and side-sections, of a seat-member adapted to set across the top of the frame and to slide thereon, a correspondingly-formed extension-member adapted to set on top of the frame in alignment with the seat-member, said seat-member and extension-member arranged to be drawn out in opposite directions to bring them into position on the top of the frame, rollers on the ends of the extension-member, and in 70 inclined guiding-tracks on the end-sections of the frame adapted to receive the rollers on the extension-member to guide the latter down into position within the sides of the frame underneath the seat-member. 80

2. In a convertible couch-bed or davenport, the combination with a box-like body, of a seat-member adapted to set across the top of the body, a correspondingly-formed extension-member adapted to be lowered 85 into the body beneath the seat-member, rollers on the ends of said members, substantially horizontal guiding-tracks in which the rollers on the ends of the seat-member travel to adapt the latter to be pulled out to 90 overhang the side of the body, and inclined guiding-tracks for the rollers on the extension-member to guide the latter from within the body of the couch into position on top thereof in alignment with the seat-member. 95

3. In a convertible couch-bed, the combination with a rectangular frame having end- and side-sections, of a seat-member adapted to set across and cover the top of said frame, rollers on the ends of the seat-member, substantially horizontal guiding-tracks on the end-sections of the frame on which the rollers travel to adapt the seat-member to be pulled out to overhang the side of the frame, an extension-member corresponding 100 in form to the seat-member, rollers on the ends of the extension-member, inclined guiding-tracks on the end-sections of the frame on which the rollers on the extension-member travel to guide the latter from within 110 the frame to a position on top thereof in alignment with the seat-member, and supporting rollers on the side-sections on which the seat- and extension-members bear as they slide across the top of the frame. 115

4. In a convertible couch-bed, the combination with a frame having end- and side-sections, of a seat-member adapted to set across the top of the frame, substantially horizontal guiding-tracks on the inside of 120 the end-sections of the frame and inclined guiding-tracks communicating with the horizontal tracks at their upper ends, rollers mounted on the ends of the seat-member to travel in the horizontal tracks when said member is pulled out to overhang the side of the frame, an extension-member corresponding in form to the seat-member and 125

adapted to fit within the frame, and rollers on the extension-member adapted to travel in the inclined tracks and to enter the horizontal tracks to bring said member into alignment with the seat-member when both members are pulled out to overhang the sides of the frame.

In testimony whereof I affix my signature in presence of two witnesses.

NOEL L. ANTHONY.
